LADDER OPERATING MECHANISM

Eugene G. Humpal and Roy O. Balogh, Cleveland,
Ohio, assignors, by mesne assignments, to
McCabe-Powers Auto Body Co., St. Louis, Mo.,
a corporation of Missouri

Application July 7, 1949, Serial No. 103,484

4 Claims. (Cl. 228—8)

1

This invention relates to a mechanism for mounting a ladder and controlling it to enable it to be swung laterally and elevated and extended as desired. An object of the invention is to provide effective controlling mechanism for such movements so arranged that they may all be operated by one operator from a single position.

Our extension ladder is pivoted to a supporting member which is swiveled on an upright standard. This standard, if desired, may be carried by a transporting vehicle. Suitable manually operated mechanism between the standard and the supporting member is provided to swing the ladder laterally. Hydraulic mechanism between the supporting member and ladder enables the ladder to be swung upwardly on its pivot or lowered into horizontal position for transportation. Mechanism on the ladder itself including its extension provides means for effecting such extension under manual control.

The upright standard is preferably hollow and provides the receptacle for the liquid used in the hydraulic operation. The control valves for the hydraulic operation are mounted on the swiveled supporting member. We provide two hand wheels on opposite sides of the device one for operating the lateral swinging mechanism and the other for effecting the ladder extension. We provide preferably a foot lever for operating the control valve. The ladder carries a depending support for the operator between the two hand wheels and adjacent the foot lever, so that in one position he may operate all three controls.

Our invention includes the features of operation above-mentioned, and also the more specific embodiment thereof illustrated in the accompanying drawings, which show a preferred form of our invention.

In the drawings, Fig. 1 is a side elevation of our ladder and its support mounted on a transporting vehicle, of which a portion is shown; Fig. 2 is a horizontal section in a plane indicated by the line 2—2 on Fig. 1, showing the manually operated gearing for swinging the ladder laterally; Fig. 3 is a diagram illustrating the conduits and connections and valves for controlling the hydraulic operation which swings the ladder upwardly and downwardly on its pivot; Fig. 4 is a sectional side elevation, in a plane parallel with Fig. 1 but on a larger scale, showing the hydraulic operation and the lateral swinging mechanism; Fig. 5 is a vertical section through the ladder supporting member in a plane at right angles to Fig. 4, as indicated by the line 5—5 thereon, but on a smaller scale; Fig. 6 is a view in the nature of a plan, as indicated by the line 55

2

6—6 on Fig. 1, showing the mechanism for extending the ladder; Figs. 7, 8 and 9 are diagrams showing the position of the controlling valves respectively for holding the ladder at any angle and for raising it and for lowering it.

In Fig. 1 we have indicated at A any suitable transportation vehicle which carries an upright hollow standard 10 on which our ladder is mounted. This vehicle also carries a suitable power-operated pump, not shown. The standard 10 which is hollow forms the reservoir for liquid used for the hydraulic operation, and a conduit from the pump communicates with this hollow standard. A conduit within the standard as hereinafter explained, leads to the control valve for operating the hydraulic ladder lifting mechanism, and a return conduit from the control valve leads to the interior of this reservoir.

Referring more particularly to the hollow vertical standard 10, this is best shown in Fig. 4, and comprises an upright cylindrical body reinforced at its lower portion by an embracing cylinder 11 which rests on and is welded to a bottom plate 12 which is mounted on top of the vehicle or other suitable support. We have shown a bottom disc 13 within the surrounding sleeve 11 and welded to it for forming the bottom support for the standard 10, which is also welded to this disc. We also provide a second disc 14 within the tube 10 and welded to it. These two discs 13 and 14 are additionally locked together by a bolt 15. Thus all of the parts mentioned are rigidly connected together for effectively carrying the standard 10 in vertical position.

In addition to being a receptacle, the tubular standard 10 forms the support for the rotary member to which the ladder is pivoted. This is effected by a head 16 on the tube 10 which carries an upright cylindrical extension 19 on which other members are mounted as hereinafter explained.

The swiveled ladder support is a tubular member 20 surrounding the member 10 and at its lower end carries a rubbing bearing 21 engaging the exterior of the reinforcing sleeve 11. At the upper end of the cylinder 20 is a transverse plate 22 to which is bolted a collar 23. A rolling bearing is provided between the collar 23 and the stationary tubular support 19. As indicated, in Fig. 4 this bearing comprises a double conical roller arrangement 24 which provides both for the thrust and rotation.

The horizontal plate 22 at the top of the cylinder 20 is of rectangular formation, the smaller dimension of which is the same as the external diameter of the tube 10. Embracing this rec-

tangular plate is a box-like rectangular structure having side plates 25, tangent to the cylinder 20 and welded to it, end plates 26, partitions 27 and a top plate 28. This rectangular extension of the tube 20 furnishes the pivotal support for the ladder, as hereinafter explained.

The main ladder has a pair of side rails 30 and suitable rungs 31. These side rails are pivoted to the rotary supporting structure by means of a pair of pivot bolts 32 which occupy stationary sleeves 29 mounted in the vertical plates 26 and 27 carried by the tube 20 and welded to the plates, as illustrated in Fig. 5. The ladder rails are journaled on the bolts 32 which have heads 33 and nuts 34 screwing onto their inner ends to form a lock, holding the bolts in stationary position and thus effectively pivoting the ladder to the rotating member 20.

The stationary extension 19 of the head 18 of the standard 10 rigidly carries a worm wheel 40 located above the bearing 24 and keyed to the extension. The partition walls 27 of the box-like extension of the tube 20 carry bearings 42 (Fig. 2) in which is rotatively mounted a shaft 43 carrying a worm 44 meshing with the worm wheel 40. In the outer end of the shaft 43 is a hand wheel 45. This hand wheel and the worm gearing provide readily operable manual means for turning the member 20 and the parts it carries on the standard 10 and thus swinging the ladder laterally, as desired.

Slidably guided on the ladder rails 30 are the rails 50 of the extension ladder, this ladder carrying suitable cross rungs 51. Any of the usual means for effecting the sliding connection between the two ladders may be employed; hence, they are omitted in Fig. 6, which is concerned with the operating mechanism.

Mounted on the rails 30 of the main ladder is a rotary shaft 52 carrying a drum 53 about which is wound a cable 54. This cable extends upwardly over pulleys and operates to raise the extension ladder. As shown, the cable 54 passes over a pulley 55 carried by the outermost rung 31 of the main ladder and thence downwardly beneath and across two pulleys 56 carried by the extension ladder and thence upwardly where it is anchored at 57 to the outermost rung of the main ladder. A suitable hand wheel 58 on the shaft 52 provides for rotating it, and thus paying the cable in or out to raise the extension ladder with reference to the main ladder or to control its descent.

At their rear ends the rails 30 of the main ladder carry a cross rod 61 on which is pivotally connected a depending foot support 60 which has preferably several cross bars 62 to support the operator in any elevation desired. It will be seen that the operator standing on one of the cross bars 62 and facing the standard and ladders is in position to operate the hand wheel 45 by his right hand to swing the ladders laterally, and by his left hand to operate the hand wheel 58 to operate the extension of the ladder.

The hydraulic operating member comprises a cylinder 10, and a piston 11 within it on the lower end of a rod 12. The cylinder at its lower end is pivotally connected to the rotating support 20, and the piston rod at its upper end is pivotally connected to struts depending from the ladder.

As shown in Figs. 1 and 4, we secure a collar 13 about the lower portion of the tube 20. This collar has a radially projecting ear 14 which is embraced by a bifurcated ear 15 projecting downward from the head 16 of the cylinder. A pin 17

pivots these members together. The upper end of the piston rod is shown as pivoted to a fitting 36 which is at the junction of a pair of struts 37 and 38 depending from the ladder 30. These struts extend between the rails of the ladder and are rigidly secured to the cross members secured to the ladder, one of these cross members being shown at 39 in Fig. 4.

Pivoted to one side of the rotary supporting member 20 is a foot lever 81, which operates the valve 80, also mounted on the member 20, which controls the passage of fluid under pressure through the conduit designated 5 at the lower portion of the cylinder. This foot lever 81 is in position to be operated by the right foot of the operator standing on the support 60. The operator may thus actuate the valve to transmit fluid under pressure to the bottom of the cylinder to shove the piston upwardly and thereby swing the ladder on its pivot 32; or to hold the liquid within the cylinder and thereby hold the ladder in a definite position, or to release such liquid and thereby allow the ladder to descend by its own weight. This hydraulic operation will be best understood from the arrangement of conduits in Figs. 1 and 4 and the diagrams of Figs. 3 and 7, 8 and 9.

The conduit designated 6 in Fig. 4 and in the diagrams leads to the pump from the lower portion of the receptacle 10, being coupled to a nipple 16 discharging into the receptacle. Another conduit designated 1 comes from the pump to a coupling 82 which connects it with an inside elbow 83 from which elbow a conduit 84 leads upwardly through the hollow bearing and stationary sleeve 19 to a stationary cylindrical plug 85 carried by such sleeve. This plug 85 has in its exterior surface an annular groove 86 with which the conduit 84 communicates. Surrounding the stationary plug 85 is a sleeve 87 carried by the top portion of the rotating member 20. Extending outwardly from this sleeve 87 is a conduit 88 passing to the exterior of the rotary support and thence continuing downwardly by an external conduit 89 leading to the control valve 80.

It results from the connection just described that the control valve is always in communication with the conduit 1 from the pump irrespective of the lateral position of the ladder and the corresponding lateral position of the control valve carried by the rotating member 20.

The stationary cylindrical plug 85 is provided with another internal vertical passageway in communication with another annular groove 90 in its exterior. A conduit 92 leads downwardly from this passageway to the interior of the cylinder 10. The same vertical passageway extends to the top of the plug where it communicates with the interior of a breather valve having a removable cap 93. A conduit 95 extends from the sleeve 87 outwardly through the exterior of the plate 25 of the rotary member and is there connected to a conduit designated 2 leading to the control valve.

It will be seen that the conduit 2 from the control valve is always in communication with the interior of the receptacle 10 irrespective of the lateral position of the ladder and control valve. The removal of the cap 93 of the breather furnishes ready means for supplying fluid as may be necessary to the interior of the receptacle 10 through the passageway 92.

Associated with the hydraulic control 80 is a pilot-operated check valve 100 also mounted on the cylinder 20. This pilot-operated check valve,

as shown in Figs. 7, 8 and 9, includes a closed casing having an internal valve seat 101; a plug 102 cooperating with said seat; a spring 103 tending to press the plug to its seat, and a piston 105 in the cylindrical portion of the casing 100 having a piston rod adapted to pass through the valve seat and unseat the valve plug 102.

The conduit 5 from the cylinder is connected to the pilot-operated valve on the plug side of the valve seat. A conduit 3 from the control valve leads to the cylinder on the other side of the seat and in advance of the piston 105, and a conduit 4 leads from the control valve to the pilot-operated check valve on the other side of the piston 105.

In the normal, idle or holding position of the ladder lifting mechanism, the plug 102 of the pilot-operated check valve is held on its seat by the spring 103. The control valve 80 is indicated as having a multi-piston cylindrical controlling plug 110. In the holding position, Fig. 7, this controlling plug blocks both the passageways 3 and 4. Thus the conduit 1 from the pump is connected merely through the diagonal passageways 111 of the piston of the plug to either of the conduits 2 (two parallel conduits 2 being shown in Figs. 7 and 8) back to the reservoir 10. As the reservoir is in constant communication with the pump via the conduit 6, the result is that in the neutral position the pump may operate idly, merely circulating liquid to and from the reservoir.

When it is desired to raise the ladder the control plug 110 is shifted by its foot lever 81 into the position shown in Fig. 8. In this position the conduit 1 from the pump is coupled to the conduit 3 so that fluid under pressure passes to the pilot-operated check valve and by its pressure forces the plug 102 from its seat and thence passes to the conduit 5 and the cylinder to raise the ladder. It will be noticed that in this position of the control valve the additional conduit 4 to the check valve is idle, being merely coupled to the reservoir.

To lower the load, the valve plug 110 is shifted in the opposite direction into the position shown in Fig. 9. In this position the conduit 3 between the control valve and the check valve is disconnected at the control valve from the pump but is connected with the reservoir. On the other hand, the line 1 from the pump is coupled to the line 4, conveying pressure to the cylinder portion of the check valve to force the plunger into position to unseat the valve. This couples the conduit 5 from the cylinder with the conduit 3 and thence to the conduit 2 back to the reservoir, so that the pressure liquid in the cylinder is freed and the ladder may descend by its own weight. When it has descended the desired distance, a shifting of the plug 110 to neutral position (Fig. 7) terminates the descent of the ladder.

By the simple provision of the control valve, the pilot-operated check valve and conduits, as described, the operator standing on the support 60 may readily effect the raising or holding or lowering of the ladder, as described.

It will be seen from the description given, and the illustrations in the drawings, that we have provided a self-contained supporting, operating and controlling device adapted to be mounted on a vehicle or other suitable support and serving not only to carry the ladder during transport of the vehicle but to operate it to swing it, raise it, and extend it, as desired, all such operations 75

being readily controlled by one man standing on the supporting device depending from the ladder.

By making the tubular stand for swivelly supporting the pivoted ladder hollow and providing it with suitable conduits, we save the necessity of any outside tank. We have also housed the lateral turning mechanism within a hollow portion of the ladder-supporting device, where it is thoroughly protected. This same rotary supporting member also carries the control valve, its associated pilot-operated check valve, and the controlling foot-lever. We have thus consolidated the various requirements and their operation into a comparatively small space all self-contained and ready for mounting, as desired, on any suitable vehicle or elsewhere.

We claim:

1. The combination of an upright standard, a supporting member swiveled on the standard on a vertical axis, a ladder pivoted to the supporting member on a horizontal axis, an operator's support disposed in downwardly extending relation to, and rotatable with, the ladder, a stationary worm wheel carried by the standard in a horizontal plane, a rotatable worm mounted in the supporting member and coacting with the worm wheel, and means adapted for manipulation by an operator on said operator's support for turning the worm.
2. The combination of an upright stationary cylinder adapted to form a supporting standard and a reservoir, a head on said cylinder, said head carrying a tubular plug having two longitudinal passageways therein, conduits connecting one of said passageways with a source of fluid supply under pressure and connecting the other passageway with the interior of the cylinder, said passageways terminating in independent annular grooves on the exterior of the plug, a tubular supporting member surrounding said cylinder and mounted to turn on the axis of the cylinder, said supporting member having a sleeve surrounding said plug, a pair of conduits leading from said sleeve to the exterior of the supporting member and there connected with a control valve carried by the supporting member, a ladder pivoted to the supporting member, a piston and cylinder connected to the supporting member and ladder for raising the ladder, and a conduit between the control valve and the cylinder for transmitting fluid under pressure to the cylinder to raise the ladder.
3. The combination of a stationary upright hollow cylinder forming a supporting standard and a reservoir, a head on said cylinder, a tubular supporting member surrounding the cylinder and operatively bearing against the exterior of the cylinder near the lower end of the supporting member, an axial thrust bearing operatively mounted between the cylinder and the head on said standard, a stationary worm wheel carried by the head of the cylinder, a worm journaled in the supporting member to coact with said worm wheel, a stationary tubular plug carried by said head above the worm wheel, a sleeve carried by the supporting member surrounding said plug, two independent conduits carried by the supporting member and extending through said sleeve to communicate respectively with the passageways in the plug, one of said passageways communicating with the interior of the standard, a conduit within the standard connecting the other passageway with an external source of supply, a ladder pivoted to said supporting member, a piston and cylinder couple one end of which is

7
pivoted to the ladder and the other end of which is pivoted to the supporting member near the lower end thereof, a control valve carried by the supporting member and communicating with said two conduits leading to the plug, and a conduit establishing communication from the control valve to the cylinder of said couple.

4. An aerial ladder comprising a base, a hollow vertical cylinder mounted on and extending upwardly from the base and closed at its ends to provide a reservoir for hydraulic fluid, pump means for supplying hydraulic fluid under pressure to the reservoir, a tubular post mounted concentrically upon the cylinder for rotation about the vertical axis thereof, a ladder element mounted on the upper end of the post for rockable movement about a horizontal axis, an extensible hydraulic piston-cylinder assembly rockably connected at its one end to the post and at its other end to the ladder element outwardly of the horizontal axis about which said latter element pivots, a first conduit connecting the reservoir with the piston-cylinder assembly, a check-valve interposed in said line, said check-valve having hydraulic actuating means whereby it may be opened, a second conduit connecting the hydraulic actuating means of the check-valve to the reservoir, a multiplex valve interposed in both conduits and connected also by an auxiliary
